(57) CLAIM

The ornamental design for a cap for a chair leg, as shown and described.

DESCRIPTION

FIG. 1 is a perspective view of four caps in accordance with a first embodiment of my new design, with a chair, which forms the environment of the four caps, being illustrated in broken lines, which broken lines are for illustrative purposes only and form no part of the claimed design;

FIG. 2 is a front elevational view of a first of the caps shown in FIG. 1;

FIG. 3 is a left-side elevational view thereof;

FIG. 4 is a right-side elevational view thereof;

FIG. 5 is a bottom view thereof;

FIG. 6 is a top plan view thereof; and,

FIG. 7 is a sectional view taken along line 7—7 of FIG. 6.
